HAIR COMB

George R. Collins, Monroe, Mich.

Application May 16, 1950, Serial No. 9,988

Term of patent 14 years

(Cl. D86—8)

To all whom it may concern:

Be it known that I, George R. Collins, a citizen of the United States and a resident of Monroe, Monroe County, Michigan, have invented a new, original, and ornamental Design for a Hair Comb, of which the following is a specification, reference being had to the accompanying drawing, forming a part thereof.

In the drawing:

I claim:

The ornamental design for a hair comb, as shown.

GEORGE R. COLLINS.
